UNITED STATES PATENT OFFICE.

FREDERICK W. LOVELL, OF CLEVELAND, OHIO, ASSIGNOR TO THE McMYLER MANUFACTURING COMPANY, OF CLEVELAND, OHIO, A CORPORATION OF OHIO.

CAR-DUMPING APPARATUS.

No. 851,014.

Specification of Letters Patent.

Patented April 23, 1907.

Application filed August 31, 1906. Serial No. 332,731.

To all whom it may concern:

Be it known that I, FREDERICK W. LOVELL, a citizen of the United States, residing at Cleveland, in the county of Cuyahoga and State of Ohio, have invented a certain new and useful Improvement in Car-Dumping Apparatus, of which the following is a full, clear, and exact description.

The object of the present invention is to so improve car-dumping apparatus as to the better adapt it to the conditions obtaining in its use.

The invention more particularly relates to a construction and arrangement whereby the adjustable apron into which the car is dumped may be pulled up and out of the way in such manner as to clear the rigging of vessels and to conform to the United States regulations with regard to projections over the dock-line and at the same time permit the tower to be constructed and maintained close to the dock-line in order to obtain the obvious benefit which comes from the proximity between the two.

Referring to the accompanying drawings, which illustrate an embodiment of my invention, Figure 1 is a side elevation of a hoisting-tower with the dumping pan or apron shown in full lines in a retracted or upright position, the apron being also shown in dotted lines in the position which it occupies when being used. Fig. 2 is a top plan view of the hoisting-tower, the dumping-apron being omitted.

My tower is like other towers of this type, provided with a framework comprising corner-posts A' A² A³ A⁴, which are connected with the rest of the structure by cross-bracing and in such manner as to be as stable as possible. At the top of the framework of the tower I provide side girders A⁵ A⁶, extending from the posts A' A² at the front or apron side of the tower to the rear posts A³ A⁴. These side girders are secured in any suitable manner and carry between them transverse girders B' B², the transverse girder B' extending from one side to the other across the top of the tower. This girder B' is set back some distance from the front posts A' A², previously referred to, in order to allow a clear space between these posts for a purpose hereinafter described.

Adjacent to the front posts and in the present instance hanging from supporting plates C at the top of said posts are the usual screw-

rods C' C², on which the dumping-apron D is carried, the apron being pivotally trunnioned to nuts carried by said screw-rods C' C² and being therefore vertically adjustable by the rotation of these rods.

The apron which I employ is of the usual type, being A-shaped—that is to say, broad at its inner end and tapering toward a point at its outer end D' at which it carries a telescoping funnel or chute D², such as is commonly used in the art. The outer end of this apron is supported by means of ropes D³, attached near its extreme outer and lower corner D⁴. These ropes are reeved over sheaves D⁵ at the top of the tower, as will be subsequently described, and in order to prevent the rope from catching on the sides of the A-shaped apron when the latter is in its lowered position I provide on the outer and upper end of the apron a more or less circular casting D⁶, over which the rope is led, so that it will be held away from the sides of the apron when the latter is in the lowered position.

At the top of the tower are several short girders A⁷, resting on the two transverse girders B' B² previously described. These short girders carry thereon the sheaves D⁵, over which are reeved the ropes attached to the outer end of the dumping-apron, the ropes being led down to a hoisting-drum E at the bottom of the tower. As will be seen from Fig. 2, these sheaves D⁵ are, owing to the structure just described, set back and in away from the front edge of the tower, so that when the apron is raised the outer end D' of the latter may pass in between the forward posts A' A² and screw-rods C' C² above described. By having this structure in which the forward transverse girder B' and the hoisting-sheaves D⁵ are set back so as to allow a clear space between the screw-rods C' C² by which the apron is pivotally supported I am enabled to draw up the apron to such an extent that it does not project out so far as to interfere with the rigging of boats and so as not to hang over the dock-line to any extent and yet obtain this advantage without in any way lengthening the apron or increasing the dimensions of the tower. It will be seen that the apron is, as heretofore, pivoted on a line with the front face of the tower and is not of necessity altered as to its dimensions. It is a characteristic feature of

my invention that the length of the apron and distance of the front face of the tower from the dock-line may each remain the same as heretofore and yet the apron be withdrawn, so as to clear the obstructions and conform to the regulations, which it was hitherto impossible to do with the same length of apron and the same proximity of the tower to the dock-line.

10. I have indicated in my drawings several conventional and ordinary structures, such as the car-dumping platform and the sheaves and other pieces of apparatus by which the apron and telescoping chute are manipulated; 15 but inasmuch as these are well known to everyone in the art and I do not claim any novelty therefor I have not encumbered the application by describing them.

Having thus described my invention, I 20 claim—

1. In combination a tower and a dumping-apron pivotally supported at one side of the tower and having hoisting-ropes, a forward transverse girder carrying supports for 25 sheaves for the hoisting-ropes of the apron, said girder being set back of the vertical plane of the points of pivotal support of the apron so as to afford a clear space above said 30 points of support into which clear space a portion of the apron may be drawn.

2. In combination a tower and a dumping-apron pivotally supported at the front of the tower, a forward transverse girder at the top of the tower set back from the front of the tower so as to afford a clear space into which 35 the outer end of the apron may be drawn.

3. In combination a tower and a dumping-apron pivotally supported near the front side of the tower, said apron having near its outer upper end a bearing-surface, a hoisting-rope 40 attached to the outer lower end of said apron and passing over said bearing-surface and reeved over sheaves at the upper part of the tower and attached to a hoisting-drum.

4. In combination a tower and a dumping-apron, said apron pivotally supported near 45 one side of the tower and adapted to swing upward, a girder near the top of the tower extending parallel with said side and set back beyond the vertical plane of the pivotal supports of the apron so as to provide a clear space in the upper part of the tower into which the outer end of the apron may be drawn.

In testimony whereof I hereunto affix my 55 signature in the presence of two witnesses.

FREDERICK W. LOVELL.
